UNITED STATES PATENT OFFICE.

JACQUES SCHNEIDER, OF SOLOTHURN, ERNST HÜRLIMANN, OF ZUCHWIL, AND FRÉDÉRIC BILLON, OF SOLOTHURN, SWITZERLAND, ASSIGNORS TO THE FIRM SCINTILLA, OF SOLOTHURN, SWITZERLAND.

CABLE-OUTLET OF MAGNETO-ELECTRIC-IGNITION MACHINES FOR INTERNAL-COMBUSTION ENGINES.

1,397,148.

Specification of Letters Patent.

Patented Nov. 15, 1921.

Application filed August 22, 1919. Serial No. 319,235.

To all whom it may concern:

Be it known that we, JACQUES SCHNEIDER, a citizen of the Swiss Republic, residing at Solothurn, Switzerland, ERNST HÜRLIMANN,

a citizen of the Swiss Republic, residing at Zuchwil, Canton Solothurn, Switzerland, and FRÉDÉRIC BILLON, a citizen of the Swiss Republic, residing at Solothurn, Switzerland, have invented certain new and useful Improvements in Cable-Outlets of Magneto-Electric-Ignition Machines for Internal-Combustion Engines, of which the following is a specification.

In order to provide a manifold guarantee against the continued working of an internal combustion engine, it is usual to provide an apparatus by means of which the interrupter-contacts of the primary circuit of the ignition machine can be bridged, so that the high voltage impulses that are necessary for generating the igniting sparks can no longer occur in the secondary circuit, and therefore no ignition can take place.

Since the primary circuit is connected at one end to the machine casing, only the other end has to be passed out through the insulating device. This is done according to the present invention in the middle of the machine casing between the two insulating parts that contain the leading-in bushes for the sparking plug cables.

The accompanying drawings illustrate a constructional example of this invention, in which—

Figure 1 shows a front elevation of a constructional example of one part of the ignition machine.

Fig. 2 is a longitudinal section through the center line of Fig. 1.

The machine is of a special constructional form of magneto, with rotating magnet and stationary coil the casing *c* of which is provided with two symmetrically arranged insulating parts *b* through the holes *c* of which the cable leads are led to the sparking plugs.

Between these there is situated the insulated leading-in bush *d* of the short circuiting cable *e* of the primary circuit winding *f* of the ignition apparatus.

In order to allow of removing the winding independently of the short circuiting cable and without undoing any terminal screw, the electric connection between the short circuiting cable *e* and the winding is effected by means of a spring press contact which is shown in Fig. 2 of the drawings as being constituted by a laminated brush *g*, but which might also be constructed in the form of a contact spring or finger or the like.

As shown in Fig. 2, the brush *g* bears upon a metal disk which is electrically connected to the end of the primary winding *f* and which is mounted on the condenser *h*.

What we claim is:—

1. A magneto electric ignition machine including a primary and a secondary winding, a casing, two symmetrically arranged insulating pieces for the leading out of two high tension leads from said secondary winding and a third insulating bush arranged symmetrically between said first mentioned insulating pieces for the leading out of a cable for short circuiting the primary circuit.

2. A magneto electric ignition machine including a primary and a secondary winding, a casing, two symmetrically arranged insulating pieces for the leading out of two high tension leads from said secondary winding, a third insulating bush arranged symmetrically between said first mentioned insulating pieces for the leading out of a cable for short circuiting the primary circuit, and a spring press contact connecting said primary winding to said short circuiting cable located in the interior of the machine casing.

In testimony whereof we have signed our names to this specification.

JACQUES SCHNEIDER.

ERNST HÜRLIMANN.

FRÉDÉRIC BILLON,
